UNITED STATES PATENT OFFICE.

ARCHIBALD E. LINGO, OF COLLINGSWOOD, NEW JERSEY, ASSIGNOR TO JOHN E. LINGO & SON, INC., OF CAMDEN, NEW JERSEY, A CORPORATION OF NEW JERSEY.

METHOD OF MAKING COLUMNS.

Application filed June 9, 1927. Serial No. 197,663.

This invention relates to a method of making columns.

This invention further relates to the making of columns having either a straight taper or an entasis, and is especially adapted to the making of columns which are to be used as flag poles or the like, and the principal object of the invention is to provide an improved process of forming such columns.

10 A further object of this invention is to provide an improved method of making a column in sections which may be assembled without the use of rivets or bolts and yet have in its finished form a smooth curvature 15 or taper from end to end without breaks in the contour thereof.

Columns which are first fabricated in sections, and later assembled without the use of rivets or bolts, have been known in the art. These, however, have usually been of the type in which the adjoining ends of the sections are telescoped with respect to each other, and they are open to the objection that the finished column does not have 25 a smooth taper, but, on the contrary, breaks in the tapered line appear at the points where one section telescopes into the other. These columns are further objectionable on the ground that it is practically impossible 30 to form a column having a straight tapered appearance by giving the column the proper entasis.

In the manufacture of steel flag poles, a wide variety of sizes is called for, including 35 varying lengths, varying diameters at several points along the respective lengths, and varying thicknesses of the walls at different points in the respective lengths of the poles.

Attempts have heretofore been made to 40 construct tapered flag poles from sheet metal by initially cutting the metal to the necessary trapezoidal shape, and thereafter forming the same into the tubes from which the pole is built up.

45 Such poles, however, as have been so constructed have not been well received in the trade, as they have necessarily been made in but a few sizes, and, owing to shop limitations the same have been made with relatively thin walls, and of too large diameters, to render them acceptable except under certain limited conditions.

To attempt to manufacture flag poles directly from sheet metal, with the wide

variety of lengths, diameters at several 55 points along the respective lengths, and wall thicknesses throughout the respective lengths, as called for in the trade, would require an expenditure for shop equipment which would be prohibitive.

60 These and other difficulties have been overcome by the improved method of forming columns of the type herein described.

More specifically stated, one of the objects of this invention is to provide an improved 65 method of making a column which will have a smooth, continuous taper.

A further object of this invention is to provide an improved method of making an assembled column which may, if desired, be 70 formed with the proper entasis to present a pleasing appearance.

A further object is to provide an improved method of making an assembled column which will be practically a one- 75 piece structure after completion.

A further object is to provide an improved method of making a column for use as a flag pole or the like in which the wall thickness may be varied throughout the length 80 to provide the greatest possible strength with a minimum of weight.

A further object is to produce an improved method of making an assembled column for use as a flag pole or the like 85 which column will possess unusual strength, durability, and be practically a one-piece structure after completion, and which may be economically made.

The nature and characteristic features of 90 my invention will be more readily understood from the following description, taken in connection with the accompanying drawings forming part hereof, in which:

Figure 1 shows a finished column, in this 95 case intended for use as a flag pole;

Fig. 2 is a perspective view of one of the sections making up the column and also showing the first step in the process of forming the column;

Figs. 3, 4 and 5 are views similar to Fig. 2, but of sections of successively smaller initial diameter than that disclosed in Fig. 2, the same being used for forming the progressively smaller sections of the column;

100 105 Fig. 6 is a fragmentary section showing in conventional detail two abutting sections and means for uniting the same, as well as

the reinforcing means preferably used to strengthen the column at the points of juncture of the sections;

Fig. 7 is a section taken on the line 7—7 of Fig. 6;

Fig. 8 is a fragmentary section showing in detail two abutting sections and a modified form of reinforcing means used to strengthen the columns at the points of juncture of the sections;

Fig. 9 is a section taken on the line 9—9 of Fig. 8; and

Fig. 10 is an end elevation of one of the sections in the swaging blocks used for forming the sections at one stage of the process.

Referring to the drawing, in the particular embodiment of my invention therein shown, 1 denotes a column which may be composed of a single tubular section, or a plurality of sections 2, as the case may require in each particular instance.

The ends of each of the sections are beveled or chamfered as at 3. Each section is also preferably provided with a plurality of apertures 4 near the ends thereof.

Reference numerals 5 and 6 refer to reinforcing means which may be used to strengthen the column at the points of juncture of the different sections—numeral 5 referring to structural angles, while reference numeral 6 designates tubular reinforcing means.

Having described the component parts of the applicant's device, the method by which it is constructed will now be set forth.

The starting point is a tubular section, preferably a length of pipe such as may be readily procured in the market in stock sizes and various thicknesses. If the column desired is below a certain height, only one section is necessary; otherwise a plurality of sections are used.

A slot 7 is first cut in the tube. This slot is of elongated V-shape, and if the column is to be given an entasis, the edges of the slot are correspondingly curved. The cutting is preferably done by means of an acetylene cutting torch, although, of course, it will be understood that other means for cutting the slot may be employed if desired.

After the slot of the desired shape is cut in the tube, the tube is then placed in a press (not shown) between swaging blocks 8—8, and swaged to bring the margins of the slot together, the tube being constantly turned during the swaging operation, as well as being moved lengthwise, thereby to close the slot and form the tube into the proper tapered shape. After the margins of the slot have thus been brought together, and the section of the column formed to shape, the adjoining edges of the slot are then welded together, preferably by means of the well known arc welding process, although here

again it will be understood that other means of welding the edges of the slot may be employed if desired.

To construct a column which requires more than one section, a plurality of sections is first formed as outlined above, the same, however, being of progressively decreasing size according to the amount of taper required. These are then provided with holes 4 in any manner well known in the art. Reinforcing means 5 or 6 are now inserted in and welded to one end of the section, preferably by filling up the holes 4 with metal deposited by the arc welding process. This may be done in the shop or on the field. The sections are now fitted together as shown in Figs. 6 or 8, and welded both at the point of juncture 3 and at the remaining holes 4. This welds the sections directly to each other, forming a unitary column, and also welds the sections to the reinforcing means, thus strengthening the column at the junction point.

The above disclosure is intended as descriptive of a typical illustration of the invention, but it should, of course, be understood that many changes may be made without departing from the spirit of the invention. For instance, reinforcing means different from those disclosed may be used, or the reinforcing means may be omitted entirely in some instances, yet the column will be strong enough for the use intended. Or the column may be used for other purposes than a flag pole.

Having thus described the nature and characteristic features of my invention, what I claim as new and desire to secure by Letters Patent, is:

1. The method of making a column from a tube which consists in cutting an elongated V-shaped slot in the tube, bringing the edges of the slot together, and then uniting the same.

2. The method of making a column from a tubular section which consists in making an elongated V-shaped excision in said tubular section, then bringing the edges of said excision together, and then uniting said edges.

3. The method of making a column from a tubular section which consists in cutting an elongated V-shaped excision in said tubular section, then swaging said tubular section to bring the edges of said excision together, and then welding said edges to each other.

4. The method of making a column from a plurality of tubular sections which consists in making an excision in each of said sections, swaging each of said sections to bring the edges of the excisions together, uniting said edges to each other, mounting the sections successively one upon the other, and then uniting the abutting ends of the sections to each other.

5. The method of making a column from a plurality of tubular sections which consists in making an excision in each of said sections, swaging each of said sections to bring the edges of the excisions together, welding said edges to each other, mounting the sections successively one upon the other, and then welding the abutting ends of the sections to each other. 35
- 10 6. The method of making a column from a plurality of tubular sections which consists in cutting an elongated V-shaped excision in each of the sections, swaging each of said sections to bring the edges of the excisions together, welding said edges to each other, mounting the said sections successively one upon the other in such manner that the reinforcing means of one section extends into the abutting section, welding the said reinforcing means to the abutting section, and joining the abutting sections together. 40
- 15 7. The method of making a column from a plurality of tubular sections which consists in cutting an elongated V-shaped excision in each of the sections, swaging each of said sections to bring the edges of the excisions together, welding said edges to each other, mounting the said sections successively one upon the other, and then welding the abutting ends of the sections to each other. 45
- 20 8. The method of making a column from a plurality of tubular sections which consists in making an excision in each of the sections, swaging each of said sections to bring the edges of the excisions together, welding said edges to each other, joining reinforcing means to the ends of each of the said sections, mounting the said sections successively one upon the other in such manner that the reinforcing means of one section extends into the abutting section, joining said reinforcing means to the section into which it extends, and joining the abutting sections together. 50
- 25 9. The method of making a column from a plurality of tubular sections which consists in cutting an elongated V-shaped excision in each of the sections, swaging each of said sections to bring the edges of the excisions together, welding said edges to each other, forming apertures in the ends of each of the said sections, joining reinforcing means to the ends of each of the said sections by placing connecting means through said apertures, mounting the said sections successively upon each other in such manner that the reinforcing means of one section extends into the abutting section, joining the said reinforcing means to the abutting section by placing connecting means through the said apertures, and joining the abutting sections together. 55
- 30

In testimony whereof, I have hereunto signed my name.

ARCHIBALD E. LINGO.
